Inventor:

Thomas Stead.

UNITED STATES PATENT OFFICE.

THOMAS STEAD, OF CLEVELAND, OHIO.

IMPROVED RAILROAD-SIGNAL.

Specification forming part of Letters Patent No. **58,910**, dated October 16, 1866.

To all whom it may concern:

Be it known that I, THOMAS STEAD, of Cleveland, in the county of Cuyahoga and State of Ohio, have invented new and useful Improvements in Signals for Railroads, &c.; and I do hereby declare that the following is a full and complete description of the construction and operation of the same, reference being had to the accompanying drawings, making part of this specification, in which—

Figure 1 is a top view. Fig. 2 is a side view, and Fig. 3 an elevation.

Like letters refer to like parts.

My invention relates to the arrangement and manipulation of devices by which the signals are given, the red indicating "danger" and the white "safety."

My invention is especially applicable to the intersection of crossing of two tracks. Where it is necessary to give a signal at any angle of crossing, for this purpose I erect two signal-posts, A and B, the post A being designed for one track only, and is, consequently, stationary, while the post B is so placed as to be observed from both tracks, and is so constructed that it can be rotated upon an axis, so as to change the signals for either road at pleasure.

The usual colors of red and white are used to denote "danger" or "safety," the red always denoting "danger," red and white lights being used for the night and painted boards for the day-time.

In the stationary post the day-signals consist of the arms C D, which can be thrown out at right angles to the post at the top, as shown at C, by means of a lever, C', and connecting-rod C''; or, by means of the same devices, (shown at D' D''), the signal-board can be depressed.

The night-signal, which is attached to this post, consists of a stationary lantern, E, showing a white light upon both the view sides. For the danger-signal a disk of red glass is interposed upon both sides between the light and the approaching car. The disk F is hinged, and operated by means of a lever, F', and connecting-rod F'', by which it can be elevated or depressed at pleasure. Thus a white or red light can be shown from either

or both approaches, as desired; or a white light can be shown from one approach and a red light from the other.

It is obvious that other colors, as blue or green, can be used for other kinds of signals.

The signal-post B is supported in an upright position by means of an arm, B', through which the post passes. To the lower end of the post B is attached, below the platform, a half-wheel, G, around which a chain, G', passes. This chain G' is attached to another similar wheel, H, upon the lower end of the capstan-post H', at the same level with the wheel G.

By rotating the capstan H' one-quarter of a circle by means of the arm or lever I, the post B is also rotated one-quarter of a circle, the arm I falling into a notch in the rim of the disk I', thus securing it in place.

A lantern, K, showing two white lights, one on each side and one, (red,) I'', in front, is attached to the post B in the position shown in Figs. 2 and 3, in which position a white light would be shown in both directions in a line parallel to those upon the post A; but a red light would be exhibited in any direction approaching a right angle thereto.

By changing the lever I to the position shown at I' a red light would be shown parallel to the lights of post A.

Day-signals L are attached to the post B in the usual manner, and are manipulated the same as are the night-signals. In this way either one or both tracks can be signaled in either or both directions, at pleasure.

What I claim as my improvement, and desire to secure by Letters Patent, is—

1. The herein-described arrangement of the posts A B in relation to each other and the track, in combination with the lanterns E and K, when constructed and operated as and for the purpose set forth.

2. The wheels G and H and chain G', in combination with the post B and capstan H', lever I, and disk I', when arranged and operated as and for the purpose set forth.

THOMAS STEAD.
